UNITED STATES PATENT OFFICE.

BENJAMIN BENNETT, OF GRAPEVILLE, PENNSYLVANIA.

DESIGN FOR A GLASS VESSEL.

SPECIFICATION forming part of Design No. 25,194, dated February 25, 1896.

Application filed October 30, 1895. Serial No. 567,457. Term of patent 3½ years.

To all whom it may concern:

Be it known that I, BENJAMIN BENNETT, a citizen of the United States, residing at Grapeville, in the county of Westmoreland and State of Pennsylvania, have invented or discovered a certain new and original Design for Glassware, of which the following is a specification.

The invention described herein relates to a new and original design for glass vessels, of which the following is a specification, reference being had to the accompanying drawing, forming a part hereof, and showing in elevation a glass vessel ornamented in accordance with my design.

The leading features of the design consist in a raised central figure and circumjacent ovoidal figures arranged in a circular depression.

The design consists of a raised central figure 1, arranged within a circular depression 2. The sides of the central figure 1 are concave, the concavities 3 being substantially as illustrated. The top of the central figure is provided with a series of regularly-arranged projections. Ovoidal figures 4 are arranged around the central figure within the central depression. Fan-like figures 5 are arranged at intervals around the circular depression nearly adjacent thereto.

I claim as my invention—

The design for glass vessels, substantially as shown and described.

In testimony whereof I have hereunto set my hand.

BENJAMIN BENNETT.
